UNITED STATES PATENT OFFICE

169,952

TABLEWARE TRAY

Louis Thompson, Bandera, Tex.

Application May 20, 1952, Serial No. 19,791

Term of patent 3½ years

(Cl. D44—24)

To all whom it may concern:

Be it known that I, Louis Thompson, a citizen of the United States of America, residing at Bandera, in the county of Bandera, and State of Texas, have invented a new, original, and ornamental Design for a Tableware Tray, of which the following is a specification, reference being had to the accompanying drawing, forming a part thereof.

In the drawing:

Figure 1 is a top plan view of a tableware tray showing my new design.

Figure 2 is a side elevational view of the same.

Figure 3 is a longitudinal section of the same.

Figure 4 is a transverse sectional view taken on the line 4—4 of Figure 1.

Figure 5 is a transverse sectional view taken on the line 5—5 of Figure 1.

Figure 6 is a perspective view of the tableware tray.

The dotted line disclosure of a knife, a fork and a spoon are shown only for the purpose of illustration.

I claim:

The ornamental design for a tableware tray, as shown and described.

LOUIS THOMPSON.
